FIG. 4

INVENTOR.

Henry C. Jacobs

BY William C. Edwards Jr.

ATTORNEY.

UNITED STATES PATENT OFFICE

HENRY C. JACOBS, OF WICHITA, KANSAS

COMBINATION PLIER AND WRENCH

Application filed July 19, 1929. Serial No. 379,526.

The invention relates to an improved tool useful to mechanics, farmers, tradesmen and the public in general. The present tool is light in weight, compact and well balanced and combining the essential characteristics of many single tools into one tool, it may be readily carried and serve most uses for which pliers, hammers, wrenches, screw drivers, wire cutters, pipe holders, staple pullers, cot-
terpin pullers, tin snips, nail pullers, nut
crackers, can openers, wire twisters, bolt head
holders, hot pan holders, hog ringers and the
like are used. The various elements will be
mentioned in the description of the drawings,
15 in which Fig. 1 shows a side view of the tool
opened as a plier. The dotted position seen
in Fig. 1 illustrates maximum adjustment
of the jaw elements of the tool. Fig. 2 is a
top view of Fig. 1. Fig. 3 is a front view
20 of the tool used as pliers. Fig. 4 is a rear
view of the tool, or as used as a hammer.
Fig. 5 is a fragmentary part of Fig. 1 showing
the lower elements there seen in the dotted
position and relationship. Similar numerals
25 of reference indicate corresponding parts
throughout all the figures of the drawings.

Referring to the drawings; the tool primarily comprises a first element 10 having a T-shaped head element 11 fashioned at one end as a hammer element 12 of circular cross-section as seen in Fig. 4. The opposite end is substantially of a square effect with the under side grooved as at 13 and notched as at 14 transversely to the head element. A rounded groove in the end 15 intersects the groove 14. A plurality of holes are punched through the element 10 or so as to form a slot in the axis of the part 10. The centers of the respective hole elements of the composite slot are so spaced as to provide a plurality of constricted openings as at 16 and 17 for the slot 18. The other element of the tool is seen at 19 and carries the lower jaw element 13 α , 14 α , 15 α cooperable with the grooves 13, notch 14 and intersecting groove 15 of the element 10. The grooves 15 and 15 α cooperate as bolt head holders and for other purposes of a like nature. At 20 is seen wire cutters. The edges 21 and 22 of the parts 50 10 and 19 are ground and faced as tin snips.

A bolt 23 passed through the slot 18 engages to position the part 19 to the part 10 while allowing for the part 19 to be adjustably positioned up or down by simply engaging the bolt 23 in the proper hole of the slot as will be readily understood. This allows for receiving between the jaws 13 α —13 or at other allied parts the article to be worked upon. The lower end of the part 10 is slightly curved at 10 α and notched at 24 to be used as a tack puller. The lower end of the part 19 forms a screw driver at 25. As seen in Fig. 5 when the element 19 has been adjustably lowered, the screw driver 25 is quite a distance below the part 24, hence the part 10 does not get in the way of the work when a screw is being worked upon by the part 25.

It is obvious that the tool may be used for many other purposes and that in its compact form it fills a long felt want. Such modifications may be employed as lie within the scope of the appended claim. Having fully described my invention, what I now claim as new and desire to secure by Letters Patent is;

In a tool of the class described, a member having a top jaw portion provided with a plurality of transverse grooves on the under side thereof and a transverse notch beyond the grooves adjacent the extreme end of said portion, and a rounded groove in the end of the jaw portion at right angles to and intersecting said notch; and a second member adjustably hinged to the first mentioned member and having a lower jaw portion provided with transverse grooves on its upper face and a transverse notch beyond the grooves and adjacent the extreme end of said jaw portion, and a rounded groove in the end of said jaw portion at right angles to and intersecting said notch; the oppositely positioned paired rounded grooves of the tool functioning to hold a bolt shank with its head portion secured by the oppositely positioned paired notch portions of the tool.

In testimony whereof I affix my signature.
HENRY C. JACOBS.
